CLAIM

The ornamental design for an optical scanner, as shown in the accompanying drawings and described above.

DESCRIPTION

FIG. 1 is a top, front perspective view of an optical scanner in accordance with the present invention.

FIG. 2 is a bottom, front perspective view of the optical scanner of FIG. 1.

FIG. 3 is a bottom, rear perspective view of the optical scanner of FIG. 1.

FIG. 4 is a front elevation view of the optical scanner of FIG. 1.

FIG. 5 is a rear elevation view of the optical scanner of FIG. 1.

FIG. 6 is a right elevation view of the optical scanner of FIG. 1.

FIG. 7 is a left elevation view of the optical scanner of FIG. 1.

FIG. 8 is a top plan view of the optical scanner of FIG. 1; and,

FIG. 9 is a bottom plan view of the optical scanner of FIG. 1.

The broken lines shown herein are for illustrative purposes and form no part of the claimed design. For example, the broken lines in the form of an alternating series of relatively short dashes and relatively long dashes represent bounds of the claimed design.
